US0D1070778S

(12) **United States Design Patent** (10) Patent No.: **US D1,070,778 S**
(45) Date of Patent: ** Apr. 15, 2025

(54) **TERMINAL GROUP**

(71) Applicant: **DONGGUAN LUXSHARE TECHNOLOGIES CO., LTD.**, Dongguan (CN)

(72) Inventors: **Jianming Zhang**, Dongguan (CN); **Xiaogang Liu**, Dongguan (CN); **Rongzhe Guo**, Dongguan (CN)

(73) Assignee: **DONGGUAN LUXSHARE TECHNOLOGIES CO., LTD.**, Dongguan (CN)

(**) Term: **15 Years**

(21) Appl. No.: **29/882,374**

(22) Filed: **Jan. 13, 2023**

(30) **Foreign Application Priority Data**

Nov. 29, 2022 (CN) 202230798256.7

(57) **CLAIM**

The ornamental design for a terminal group, as shown and described.

DESCRIPTION

FIG. 1 is a front, top and right side perspective view of a terminal group showing our new design;

FIG. 2 is a rear, bottom and left side perspective view of the terminal group showing our new design;

FIG. 3 is a front plan view of the terminal group;

FIG. 4 is a rear plan view of the terminal group;

FIG. 5 is a left plan view of the terminal group;

FIG. 6 is a right plan view of the terminal group;

FIG. 7 is a top plan view of the terminal group; and,

FIG. 8 is a bottom plan view of the terminal group.

The broken lines in the drawing are for the purpose of illustrating portions of the article that form no part of the claimed design.

1 Claim, 8 Drawing Sheets
